UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 21,966, dated November 8, 1892.

Application filed October 10, 1892. Serial No. 448,450. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification, reference being had to the accompanying drawing, forming part thereof.

10 The leading feature of this design consists of a series of scroll-like ornaments of the rococo style with branches of flowers and leaves intertwined with said ornaments, as represented in the accompanying drawing. These

15 ornaments are arranged at regular intervals over the surface of the paper. On each side of said ornaments are arranged small rococo ornaments disconnected from the center ornaments.

The design is printed in any desired color 20 or colors or in bronze upon a background of any desired color.

What I claim is—

The design for wall-paper herein shown and described.

Witness my hand this 7th day of October, 25 1892.

CHARLES BOOZE.
